METHOD OF MAKING PREWELT SHOES

John H. Gaquin, Haverhill, Mass., assignor to
United Shoe Machinery Corporation, Flemington, N. J., a corporation of New Jersey

Application January 19, 1942, Serial No. 427,254

10 Claims. (Cl. 12—142)

This invention relates to the manufacture of prewelt shoes and is herein illustrated in its application to methods of making "repairable" prewelt shoes, so-called, that is, prewelt shoes which are so constructed that when a worn tread sole is removed from the shoe bottom, the welted margin of the upper will be held in place on the insole and the shoe will retain its shape.

It is the usual practice in the manufacture of prewelt shoes to last the welted margin of the upper to the edge face of a filler on the last bottom without securing the welted margin to the filler, and while the upper is held in lasted position by the wipers of the lasting machine to cement attach an outsole to the welt, the cement bond holding the shoe together temporarily until the outsole is permanently stitched to the welt. In shoes of this type the seam which secures the outsole to the welt is relied upon to hold the shoe in shape and consequently it is the usual practice to discard prewelt shoes after the tread sole is worn out since the repair of such shoes would involve a second lasting operation which would make the cost of repair prohibitive. Numerous attempts have been made to provide prewelt shoe constructions permitting repair of the shoe without a second lasting operation, but such constructions as have heretofore been proposed have been commercially impracticable because of the increased cost of production incidental thereto.

It is an object of the present invention to provide a prewelt shoe which is repairable in the sense in which that word is used above, but which, nevertheless, would cost little if any more to manufacture than prewelt shoes of the types now commonly produced commercially.

With the above object in view, the present invention in one aspect thereof consists in a method of making prewelt shoes which comprises providing a prewelt upper, providing a sole member, providing a member for connecting the welt to the sole member, shaping the upper over a last, holding the upper thus shaped on the last by means operating within the welt crease, and securing said connecting member in connecting position while the upper is so held on the last by means of a heat-responsive cement, that is, a cement which is rendered adhesive by heat. The sole member above referred to may be a filler constructed and arranged to occupy the space enclosed by the welted margin of the upper in the finished shoe, or it may be an insole in prewelt shoes which do not require a filler. A prewelt shoe of this type is disclosed in United States Letters Patent No. 1,522,564, granted January 13, 1925, on an application of Warren B. White. In accordance with the method hereinafter described, the welted margin of the upper is attached to a sole member, illustrated in the drawings as a filler of the type above described, by

means of a strip or tape coated with a suitable heat-responsive cement. This tape serves to hold the welted margin of the upper in juxtaposed relation to the edge face of the filler when a worn outsole is removed in the process of repairing the shoe. The tape is preferably initially attached to one of the parts to be connected together, the tape illustrated in the drawings being secured to the sole-attaching face of the welt by the seam connecting the welt to the upper. It will, of course, be understood that the tape may be initially attached to the filler rather than to the welt, if desired. Preferably, the tape is coated with adhesive and permitted to dry before it is initially secured to one of the members to be connected together and therefore the cement on the tape will not interfere in any way with the upper-shaping operations. Any one of a considerable number of commercial heat-responsive cements may be provided for coating the tape, the selection of cement depending mainly upon the method which is to be employed in activating the cement. While it is within the scope of my invention to activate the cement on the tape in any known manner, I have described hereinafter three novel methods of making prewelt shoes of the type above described involving specific methods of activating the cement which methods I believe to be particularly suited to prewelt shoe making. In accordance with the first method, the welted margin of the upper is lasted to the edge face of the filler and while the upper is held in lasted position, the cement on the tape is activated by the application of a heated element thereto. In accordance with the second method hereinafter described, a prewelt upper provided with the proposed filler-attaching tape is mounted on a last, then subjected to the influence of heated air to activate the cement on said tape. The upper is then lasted in the usual manner and secured in lasted position by bringing said tape into adhering contact with the margin of the filler. In accordance with the third method, hereinafter described, an upper provided with the proposed filler-attaching tape is lasted to the edge face of a filler, and while the upper is held in lasted position, the cement on said tape is rendered adhesive by radiant heat, whereupon the tape is brought into adhering contact with the margin of the filler.

The invention will now be described with reference to the accompanying drawings illustrating, by way of example, the three specific methods above referred to.

In the drawings,

Fig. 1 is a cross section of a prewelt upper supported in lasted position by the wipers of a bed lasting machine, and a portion of a heated tool operating on the shoe bottom;

Fig. 2 is a cross section of a completed pre-welt shoe on its last;

Fig. 3 is a cross section of a prewelt upper held in pulled-over position on its last by means of a clip;

Fig. 4 shows the upper of Fig. 3 in a cabinet in which the cement on the tape is activated;

Fig. 5 is a cross section showing the upper supported by the wipers of a bed lasting machine and a portion of a hammer for applying the tape to the filler; and

Fig. 6 is a cross section, similar to Fig. 5, showing a portion of a light bulb and reflector in cross section for activating the cement on the tape by radiant heat.

The drawings illustrate three methods of activating heat-responsive cement on a tape which connects the welted margin of a prewelt upper to a filler. In the method illustrated in Fig. 1, heat-responsive cement is activated by direct contact of a heated tool with the tape. In accordance with the method illustrated in Fig. 4, heat-responsive cement on the tape is activated by hot, moist air delivered to a cabinet within which the upper is placed. In accordance with the third method, illustrated in Fig. 6, heat-responsive cement on the tape is activated by radiant heat from a light bulb while the upper is held in lasted position by the wipers of a prewelt lasting machine, such, for example, as that illustrated in United States Letters Patent No. 2,045,595, granted June 30, 1936, on an application filed in the names of Alfred E. C. Hall et al.

In the preparation of shoe uppers for the manufacture of prewelt shoes, in accordance with any one of the three methods briefly referred to above, an upper 10 and a welt 12 are secured together as usual by a chainstitch seam 14. For securing the welted margin of the upper to a filler, such, for example, as the filler 16 illustrated in the drawings, there is provided a tape 18 the filler-facing surface of which is coated with a heat-responsive cement while the outsole-facing surface thereof is not treated with adhesive. The tape 18 is preferably of fabric material strong enough to resist the widthwise stress against the upper in the wear of the shoe. The tape is preferably secured to the upper 10 together with the welt 12 by the seam 14, but, if desired, it may be secured to the welt before the welt is attached to the upper. The shoe is preferably also provided with a thin insole 20 which may have been initially secured to the filler 16 or may be an integral portion thereof.

In practicing the method illustrated in Fig. 1, the tape 18 is preferably treated with an adhesive composition such, for example, as a polymerized vinyl ester, various examples of which are disclosed in United States Letters Patent No. 1,784,008, granted December 9, 1930, on an application filed in the name of Willy O. Herrmann et al. Preferably the tape, as it is provided for attachment to the upper, has been coated with adhesive and rolled so that it may be mounted on a suitable reel on the sewing machine which stitches the tape and the welt to the upper. The upper with the welt and the tape stitched to its bottom margin is mounted on a last 22 and the toe portion of the upper is pulled over and secured to the last in any known manner. The upper is then lasted in a bed lasting machine, such as that illustrated in the Hall et al. patent above referred to, said machine having lasting wipers 24 which enter the welt crease and, after lasting the upper, hold the upper in lasted posi-

tion, as illustrated in Fig. 1, while the tape 18 is secured to the filler. The application of the tape to the filler, in accordance with the method illustrated in Fig. 1, is effected by a hand tool

5 26 having a work-engaging roll 28 which is heated to a temperature sufficient to activate the heat-responsive cement on said tape. No cement need be applied to the margin of the filler provided the substance of the filler is not of a highly porous nature since the adhesive on the tape upon activation thereof will become bonded to the margin of the filler. After the tape has been cement-attached to the filler, an outsole, for example the outsole 30 illustrated in Fig. 2, is secured to the welt in any known manner, preferably by a lockstitch seam 32.

In accordance with the method illustrated in Figs. 3 and 4, hot vapor-laden air is employed to activate adhesive on the tape 18 in accordance with the method set forth in an application

20 for United States Letters Patent, Serial No. 424,877, filed December 30, 1941, in the name of M. W. Tetlow. This application teaches the use of polymerized chloroprene as an adhesive in the practice of the method therein described. In accordance with this teaching, the tape 18, illus-

25 trated in Fig. 3, is coated with an adhesive containing polymerized chloroprene and the margin of the filler is similarly treated since this 30 type of cement will not provide a satisfactory bond unless both of the surfaces to be secured together are coated therewith. In order to subject the cement-treated surfaces to hot vapor-

laden air, I prefer to employ an apparatus similar in principle to that illustrated in an application for United States Letters Patent Serial No. 375,951, filed January 25, 1941, in the name of A. J. Wells. This apparatus subjects the welted margin of the upper to the action of a vapor-

40 laden air substantially free from water in liquid form at temperatures not inimical to leather, for example, from 68° to 78° C. As herein illustrated, the apparatus for producing hot vapor-laden air comprises a cabinet 36 having in its 45 lower portion a reservoir for a body of hot water 38. Immersed in the water are perforated pipes 40 through which air is forced into said water. Said air rising through the body of water 38 is heated and becomes moisture-laden.

50 Said air after it rises from the water passes through perforated plates 42 and 44 which remove from the air all water in a liquid or visible state then contained therein. The upper on its last is supported in upright position above the plate

55 44 on parallel horizontal rods 46 secured in the side walls of the cabinet. The upper is introduced into the cabinet through an opening in the top of the cabinet, said opening being normally closed by a hinged cover 48. The cement is activated in a very short time, approximately 60 20 seconds, after which the upper is removed from the cabinet and mounted in a bed lasting machine of the type hereinbefore referred to. While the welted margin of the upper is held

65 in lasted position by the lasting wipers, the clip 34 is removed and the tape is brought forcibly into contact with the margin of the filler in any known manner, for example, by means of a rubber-faced hammer 50 (Fig. 5). An outsole is then secured to the welt by means of a lock-stitch seam or in any other known manner.

In practicing the method illustrated in Fig. 6, the tape 18 is preferably coated with an adhesive, such as that described in United States Letters Patent No. 812,384, granted February 13, 1906,

upon an application of Andrew Thoma, the main constituent of said adhesive being gutta percha. This adhesive has a melting point considerably lower than the melting point of the adhesive employed in the first method hereinbefore described and may be quickly activated by radiant heat. For producing such radiant heat, I prefer to employ an electric light bulb 52. Electric light bulbs which transmit only infra-red light rays are particularly suitable because they produce ample heat for quickly activating cement of the type above referred to without subjecting the welted margin of the upper to temperatures injurious to leather. For directing said rays toward the welted margin of the upper, said bulb is positioned within a suitable reflector 54. After the cement has been activated, the light bulb and reflector are moved into a remote position and the tape is then applied to the filler, for example, in the manner illustrated in Fig. 5. When gutta percha adhesive of the type above referred to is employed, a satisfactory bond may be obtained from a single coating of said adhesive. This coating will preferably be on the tape 18 but it will be understood that the margin of the filler rather than the tape may be coated, if desired.

It is to be understood that the specific types of cement heretofore mentioned are referred to as examples of heat-responsive adhesive suitable for use in practicing the methods above described. It will be obvious that many other types of heat-responsive cement may be successfully employed and therefore I do not limit myself to the use of the three types above mentioned.

Having thus described my invention, what I claim as new and desire to secure by Letters Patent of the United States is:

1. That method of making prewelt shoes which comprises providing a prewelt upper, providing a sole member, providing a member for connecting the welt to the sole member, shaping the upper over a last, holding the upper thus shaped on the last by means operating within the welt crease, and securing said connecting member in connecting position while the upper is so held on the last by means of cement rendered adhesive by the application of heat thereto.

2. That method of making shoes which comprises providing a prewelted upper, a sole member and a member for connecting the welt to the sole member, shaping the upper over a last, holding the upper thus shaped on the last by means operating within the welt crease, and securing said connecting member in connecting position by means of cement rendered adhesive by the application of heat thereto after shaping the upper over the last.

3. That method of making shoes which comprises providing a prewelted upper, a sole member and a member for connecting the welt to the sole member, said connecting member having a coating of heat-responsive cement, shaping the upper over a last, holding the upper thus shaped on the last by means operating within the welt crease, while the upper is so held applying heat to said connecting member to render the cement thereon adhesive, and bringing said member into adhering contact with the shoe bottom.

4. That method of making prewelt shoes which comprises providing a prewelt upper, providing a sole constructed and arranged to fill the space enclosed by the inner edge face of the welt in the

finished shoe, providing a strip for securing the welt and sole in juxtaposed position, said strip being coated with a heat-responsive cement, bringing the inner edge face of the welt into juxtaposition to the edge face of said sole by means operating within the welt crease, while holding the welt in such juxtaposed position by said means applying heat to said strip to render it adhesive, and securing the welt and sole in juxtaposed position by means of said strip.

5. That method of making prewelt shoes which comprises securing to the bottom margin of a shoe upper a sole-attaching welt and a tape treated with a heat-responsive cement, bringing the welted margin of the upper into its final position in the shoe bottom, applying said tape to a sole and rendering the cement on said tape adhesive by the application of a heated element thereto.

6. That method of making prewelt shoes which comprises securing to the welted margin of a shoe upper a sole-attaching welt and a strip coated with a heat-responsive cement, providing a sole constructed and arranged to fill the space enclosed by the inner edge face of the welt in the finished shoe, bringing the inner edge face of the welt into juxtaposition to the edge face of said sole, and applying said tape to the margin of said sole by means of a roll heated to a temperature such that the cement on said strip is rendered adhesive.

7. That method of making prewelt shoes which comprises securing to the bottom margin of a shoe upper a sole-attaching welt and a member treated with heat-responsive cement, applying heat to said member to render the cement adhesive, then bringing the welted margin of the upper into its final position in the shoe bottom and securing the welted margin in that position by bringing said member into adhering contact with a sole.

8. That method of making prewelt shoes which comprises securing to the bottom margin of a shoe upper a sole-attaching welt and a tape treated with a heat-responsive cement, bringing the welted margin of the upper into its final position in the shoe bottom and, while the upper is held in that position, activating the cement on said tape by radiant heat and then bringing said tape into adhering contact with a sole.

9. That method of making prewelt shoes which comprises securing to the lasting margin of a shoe upper a sole-attaching welt and a tape treated with a heat-responsive cement, lasting the welted margin of the upper to the edge face of a filler on the last bottom, while the upper is held in lasted position, activating the cement on said tape by radiant heat, and then bringing said tape into adhering contact with the margin of the filler.

10. That method of making prewelt shoes which comprises securing to the lasting margin of a shoe upper a sole-attaching welt and a tape treated with a heat-responsive cement, mounting on a last bottom a sole constructed and arranged to fill the space enclosed by the inner edge face of the welt in the finished shoe, lasting the welted margin of the upper up to the edge face of said sole, applying said tape to the sole, and rendering the cement on said tape adhesive by the application of a heated element thereto.

JOHN H. GAQUIN.
